CLAIM

The ornamental design for a basketball court as shown and described.

DESCRIPTION

FIG. 1 is a top plan view of a first embodiment of the basketball court, showing the new design; and,

FIG. 2 is a top plan view of a second embodiment of the basketball court.

The broken lines in the drawings illustrate portions of the basketball court that form no part of the claimed design. The basketball court is of conventional thickness that forms no part of the claimed design. The rear side of the basketball court forms no part of the claimed design.

1 Claim, 2 Drawing Sheets
